UNITED STATES PATENT OFFICE

GILLES HOLST, JAN BERGMANS, AND CORNELIS BOL, OF EINDHOVEN, THE NETHERLANDS, ASSIGNEES TO NAAMLOOSE VENNOOTSCHAP PHILIPS' GLOEILAMPENFABRIEKEN, OF EINDHOVEN, THE NETHERLANDS

LEADING-IN CONDUCTOR

Application filed May 14, 1923, Serial No. 638,931, and in the Netherlands May 27, 1922.

The present invention relates to leading-in conductors and more particularly to electric conductors which are hermetically sealed in the vitreous wall of vessels, such as the bulbs 5 of electric incandescent lamps and similar devices.

The object of the present invention is to provide a rigid and simple construction of such leading-in conductors which is especially suitable for conducting relatively heavy electric currents.

According to the present invention a disc is fused into the glass vessel, which disc consists of a metallic material which on fusing 15 in does not generate gases and has a coefficient of expansion which is little different from that of the vitreous material into which it is to be sealed, a conductor being fixed to said disc.

20 The invention is especially adapted for use in connection with discs composed of a metallic material which will be "wet" by the surrounding vitreous material. Still more particularly the invention is adapted for using chrome-iron of such composition that its 25 coefficient of expansion differs little from that of the glass.

In the case that the vessel partly consists of a tubular member of vitreous material, the 30 disc is preferably fused into the wall of said tubular member at a short distance from its end.

The leading-in conductors may be led 35 through the discs but preferably they are fixed on each side of the discs. In the case the discs consist of chrome-iron it is desirable to choose nickel for the portions of the conductors fused to the discs.

According to another feature of the invention 40 a plurality of discs is hermetically connected together along at least a portion of their circumferences by means of a layer of vitreous material, thereby forming a disc of larger dimensions, said disc being fused 45 into the vitreous wall of the vessel at its circumference and a conductor being fixed to each of the discs.

The discs are preferably sector-shaped so 50 that they form together a circular disc of larger dimensions.

The present invention relates also to a method for sealing in the discs into a wall of vitreous material. This method is characterized in first applying a thin layer of vitreous material around the circumference of said 55 disc and then sealing the disc with said glass layer into the wall of vitreous material.

In the accompanying drawing some embodiments of the invention are diagrammatically illustrated.

Figure 1 shows a leading-in conductor having the features according to the present invention with a surrounding glass tube.

In Figure 2 an arrangement according to the invention applied to an electric arc lamp 65 provided with tungsten electrodes is illustrated.

In Figure 3 is shown a lamp provided with two leading-in wires, which have been hermetically sealed.

Figure 4 shows the top-view of the stem in a lamp according to Figure 3, the pole-wires having been cut at a short distance above the stem.

Figure 5 shows a top-view of an arrangement with four leading-in wires, and

Figure 6 shows a lamp in which the discs are fused directly into the neck of the bulb.

Figure 1 shows a glass tube 1, a disc 2 and leading-in wires 3 and 4. The leading-in wires may be constructed of any suitable material of good conductivity, e. g. of copper.

As a material for the discs any metallic material may be used, the coefficient of expansion of which is little different from that of the glass and which, during the process of fusing in, generates no gases. Platinum is suitable but is expensive. It is preferable that the material should have the property of sticking to glass. Chrome-iron has this 85 property and for this reason excellent results are obtained with chrome-iron of a suitable composition.

The inventors have also recognized that the discs need not be very thin. When using chrome-iron, discs of 1-2 millimeters thickness may be fused in without any inconvenience, which has not been thought possible hitherto.

The composition depends on the nature of 100

the glass used. In general good results can be obtained when the alloy contains 15 to 50% of chromium. In one particular case for instance an alloy comprising about 17% of chromium gave excellent results.

When using the so-called "Pyrex-glass", which is much used in America, discs of molybdenum or tungsten may be also used for the purpose of the invention.

As for the coefficient of expansion of the metallic substance of the discs, the difference between this coefficient of expansion and that of the glass may be greater, than is generally possible for leading-in wires. Differences up to 20% are allowable. In a particular case, in which the coefficient of expansion of the chrome-iron was about 10% higher than that of the glass, the results were nevertheless quite favourable. It will be clear however that the smaller the difference between the coefficients of expansion, the better is the result obtained.

The leading-in wires may be fixed to the discs in various ways. They may be led through the discs and fixed to the discs by soldering, welding or in any other way. However, in doing so there is a risk of forming air-leaks at the place of introduction and it is therefore preferable to fix the leading-in wires at both sides to the discs for instance by soldering or welding. If chrome-iron discs are used, it is preferable to construct the portions, fixed to the discs, of nickel. For this metal welding is a good and easy way of fixing the same to chrome-iron.

Referring again to Figure 1, one of the leading-in wires (3) which serves to fix the electrodes or the incandescent body, may be stiff and preferably consists wholly, or at least as to the portion fixed to the disc, of nickel. The other leading-in wire (4) is preferably made flexible and may consist of twisted copper wire.

As it is rather difficult however to fix copper to chrome-iron, it is preferable to first apply a nickel current-lead also at this side of the disc and to fix the copper wire thereto, e. g. by soldering.

In Figure 2 an electric arc-lamp with tungsten electrodes is shown, provided with leading-in conductors.

The glass bulb 6 contains the glass stem 7, which ends in the tubes 8 and 9, into which the discs 10 and 11 are fused. The discs support on one side conductors 12 and 13 with the tungsten electrodes and on the other side the leading-in wires 14 and 15.

The lamp shown in Figures 3 and 4 has a bulb 16, into which the stem 17 is fused. Two crescent-shaped discs 18 and 19 are fused into this stem 17, whilst leading-in wires 20, 21, 22 and 23 are fixed on each side of the discs.

The discs may be shaped into any form desired. Preferably care should be taken that the discs can be fused together with a reia-

tively narrow glass layer between them, whilst the free part of the circumference of at least one of the discs is then fused into the wall of the glass vessel. One or more discs may also be connected with the other disc (discs) along the whole of their circumference. For instance a circular and an annular disc, can be connected by means of an intermediate annular glass layer, and then the external circumference of the annular disc, with the glass wall can be fused together.

Although it is not necessary, the most simple course is to use flat discs, which are fused together into one larger flat disc.

Furthermore the shape of the discs depends on the shape of the glass vessel at the place of fusing. If several wires are fused into a tubular part with circular section, the most simple shape for the discs is the sector of a circle, whereas in the case of two leading-in wires the crescent shape is more convenient.

In some cases it may be desirable to introduce hermetically more than two leading-in wires, e. g. for glow-lamps provided with more than one incandescent filament or in the case of discharge tubes.

Such a construction is illustrated in Figure 5 in which four quadrants 24, 25, 26, 27 are fused into the glass 28.

Referring to Figure 3 the pole wires 20 and 21 supporting the incandescent filament consist preferably of nickel, whilst also the wire-portions 22 and 23 are of nickel. The flexible wires 31 and 32, which consist of copper, may be fixed to the nickel by soldering or welding.

When manufacturing the device, the discs are preferably first connected together by a glass layer and then the aggregate obtained is fused into the glass wall for example into a tube.

The fusing is assisted by first surrounding the external circumference of the discs by a thin glass layer.

Figure 6 represents an embodiment of the invention in which the discs, with the leading-in wires fixed to them, are directly fused to the neck 29 of the bulb 30.

This is the most simple embodiment of the invention. When constructing the device according to Fig. 3 there is one step more to be performed than in the case with the device shown in Figure 6 viz, the fusing of the stem into the bulb.

The present invention may be applied to electric glow lamps and all kinds of discharge tubes such as rectifiers, generating tubes or receiving tubes, gasfilled glowlamps, vapour lamps or the like. It is particularly advantageous in cases where no good results can be obtained with leading-in wires of platinum, nickel-iron or nickel-iron with copper-coating, as generally used; particularly

in the case of heavy currents of e. g. more than 30 amperes.

What we claim is:

1. The combination of a vessel having at least a portion of its wall consisting of a vitreous material, a disc consisting of chrome-iron having a coefficient of expansion which is little different from that of the said vitreous material, said disc being hermetically fused at its circumference into said vitreous wall and forming a part thereof, and two conductors fixed each to one side of said disc and consisting of nickel at those portions which are fixed to the chrome-iron disc.
2. The combination of a vessel having at least a portion of its wall consisting of vitreous material, a plurality of discs consisting of a metallic material which on fusing-in does not generate gases and the coefficient of expansion of which is little different from that of said vitreous material, said discs being hermetically connected together along at least a portion of their circumferences by means of a layer of vitreous material, thereby forming together a disc of larger dimensions, said disc of larger dimensions being fused into said vitreous wall of said vessel and conductors fixed to said discs.
3. The combination of a vessel partly consisting of a tubular member of vitreous material, a plurality of discs consisting of a metallic material which on fusing-in does not generate gases and the coefficient of expansion of which is little different from that of said vitreous material, said discs being hermetically connected together along at least a portion of their circumference by means of a layer of vitreous material, thereby forming together a disc of larger dimensions, said disc of larger dimensions being fused into the wall of said tubular member at a short distance of the end and conductors fixed to said discs.
4. The combination of a vessel having at least a portion of its wall consisting of vitreous material a plurality of sector-shaped discs consisting of a metallic material which on fusing-in does not generate gases and the coefficient of expansion of which is little different from that of the vitreous material said discs being hermetically connected together along a portion of their circumference by means of a layer of vitreous material thereby forming a disc of larger dimensions, said latter disc being hermetically sealed at its circumference into said vitreous wall of said vessel and conductors fixed to said discs.
5. The combination of a vessel having at least a portion of its wall consisting of vitreous material a plurality of discs consisting of chrome-iron having a coefficient of expansion which differs little from that of said vitreous material, said discs being hermetically connected together along at least a por-

tion of their circumference by means of a layer of vitreous material, thereby forming together a disc of larger dimensions, said disc of larger dimensions being fused into said vitreous wall of said vessel, and conductors fixed to said discs.

6. The combination of a vessel having at least a portion of its wall consisting of vitreous material a plurality of discs consisting of chrome-iron containing more than 10% and less than 50% of chromium, said discs being hermetically connected together along at least a portion of their circumference by means of a layer of vitreous material, thereby forming together a disc of larger dimensions, said disc of larger dimensions being fused into said vitreous wall of said vessel and conductors fixed to said discs.

7. The combination of a vessel having at least a portion of its wall consisting of vitreous material a plurality of discs consisting of chrome-iron having a coefficient of expansion which differs little from that of said vitreous material, said discs being hermetically connected together along at least a portion of their circumference by means of a layer of vitreous material, thereby forming together a disc of larger dimensions, said disc of larger dimensions being fused into said vitreous wall of said vessel, and conductors fixed to each side of said discs and consisting of nickel at those portions which are connected to said chrome-iron discs.

In testimony whereof we affix our signatures.
